(57) **CLAIM**

The ornamental design for a portable spray bottle, as shown and described.

DESCRIPTION

FIG. 1 is a front perspective view of a portable spray bottle showing our new design;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken lines are included for the purpose of illustrating features of the portable spray bottle that broken lines form no part of the claimed design.

1 Claim, 6 Drawing Sheets
